UNITED STATES PATENT OFFICE.

FREDERICK E. STANLEY, OF WATERBURY, CONNECTICUT, ASSIGNOR TO
SCOVILLE MANUFACTURING COMPANY, OF WATERBURY, CONNECTICUT,
A CORPORATION OF CONNECTICUT.

BUTTON-SETTING MACHINE.

SPECIFICATION forming part of Letters Patent No. 699,721, dated May 13, 1902.

Application filed December 26, 1900. Serial No. 41,081. (No model.)

To all whom it may concern:

Be it known that I, FREDERICK E. STANLEY, a citizen of the United States, residing at Waterbury, in the county of New Haven 5 and State of Connecticut, have invented a certain new and useful Improvement in Button-Setting Machines, of which the following is a full, clear, and exact description.

The object of this invention is to provide 10 for more perfect and expeditious affixing of buttons to garments by means of tacks or similar metallic fastenings.

In that class of machines in which the tack is fed automatically to the button, provision 15 must be made for presenting the tack to the button and then permitting the action of the setting-plunger and the moving of the garment as each button is set so as to receive the button next to be set. My invention relates 20 to this set of devices and its associated parts; and it consists of a tack receiver and carrier which receives the tack from the race-way, presents it to the plunger, advances 25 with the plunger to the button until the tack-point enters the button, and then swings aside to free itself from the tack while the latter is held between the plunger and the button, so as to permit the further descent of the plunger necessary to affix the button 30 to the garment by the clenching of the tack-point within the button due to the pressure or blow of the plunger, all as I will proceed now more particularly to set forth and finally claim.

In the accompanying drawings, illustrating 35 my invention, in the several figures of which like parts are similarly designated, Figure 1 is a side elevation of sufficient of a button-setting machine to show my invention in position. Fig. 2 is a front elevation. Fig. 3 is a rear elevation, omitting the table and parts below it and the plunger-pitman. Fig. 4 is a 40 partial sectional side elevation. Fig. 5 is a horizontal section, on a larger scale, taken in the plane of line 5-5, Fig. 1, and looking down. Fig. 6 is a perspective view of the tack receiver and carrier detached. Fig. 7 is a perspective view of the escapement. Fig. 45 8 is a cross-section substantially in the plane

of the top of the bearing end of the machine-arm and on a larger scale.

The stand 1 may have a bracket 2, in which is the shaft 3, having a band-wheel 4 and a clutch mechanism 5, Fig. 2, of any approved construction for starting and stopping the machine. On this shaft is fixed a cam-disk 6, (see dotted lines, Fig. 2,) which is the actuator for the operative parts of the machine. On the stand is a table 7, and from this table rises an overhanging arm 8, in which is mounted a vertically-reciprocating plunger 9, connected by a link 10 with a lever 11, which is fulcrumed on a post 12 on arm 8. This lever 11 has its other end connected to a pitman 13, which is pivoted at 14 to the cam-disk 6. 55 This pitman may be in two parts connected by a right and left hand nut or turnbuckle 15 for adjusting its effective length. By rotation of the cam-disk the lever 11 is vibrated and the plunger reciprocated positively. 60 Alongside of the plunger and in a bearing in the arm 8 is a rod 16, having fast at its lower end an arm 17, provided with a pocket 18, made with a notch 19 and extending across into the path of movement of and beneath 65 the plunger. Above the arm 8 the rod 16 is provided with an arm 20, the hub of which is seated in an appropriate recess in the arm 8, as seen in Fig. 2, and this arm is keyed to the rod 16, (see details, Fig. 8,) so as to turn 70 it and at the same time permit said rod to move longitudinally through the said arm 20 under the pressure of the descending plunger and against the stress of a spring 21, arranged 75 around the rod above the arm 20 and beneath the cap piece or nut 22. The arm 20 has a link 23 extending rearwardly and jointed to a rocker-arm 24 on a short shaft 25, housed in a bearing 26 on the table 7, said shaft having a rocker-arm 27, which has a roller 28 in 80 contact with the cam-disk 6. (See Figs. 1 and 2.) By means of these connections with the cam-disk the rod 16 is permitted not only 85 to descend with the plunger, but it is given an axial turn which vibrates the pocketed arm 17 from beneath the plunger and free of its path of descent, as indicated by the dotted-line position, Fig. 5, and this outswing 90

of the pocketed arm is timed to occur just as the plunger is ready to give the final setting blow to the tack, as will presently appear. The pocketed arm constitutes the salient element of that which is hereinbefore and hereinafter referred to as the "tack receiver and carrier." The arm 27 and its roller 28 are held in contact with the cam-disk by spring 29, and the spring 21 suffices to lift the receiver and carrier back to starting position, Figs. 1 and 2, when the latter is freed from the plunger.

The turret or hopper 30 is mounted in a plate 31, which is secured to a bracket 32, which in turn is secured to the arm 8, and this turret has its spindle provided with a ratchet 33. 34 is a vibrating lever loosely supported upon the spindle of the turret and carrying a pawl 35, which by the vibration of the lever 34 imparts a step-by-step feed movement to the turret, and this feed movement is accomplished by means of a link 36, attached at one end to the vibrating lever and at its other end to a rocker-arm 37, pivoted to the bracket 32 and having a fork 38, which is engaged by a pin 39 on the lever 11. The plate 31 supports the raceway or tack-chute 40, the lower end of which is twisted at 41, so as to turn the tack-point down for delivery to the tack receiver and carrier and presentation to the plunger for insertion in the button.

The escapement for controlling the delivery of the tacks one by one consists of a plate 42, pivoted to the bottom of the raceway and having a bridge-piece 43, which extends over the face of the chute or raceway and has a curved slot 44, the opposite ends of which align with the slot in the raceway at different times, so that when the upper end of this curved slot is in line with the slot in the raceway a tack may enter the curved slot and be discharged from the lower end of the curved slot when the escapement is vibrated in the opposite direction to put such lower end of the curved slot in alignment with the slot in the raceway. The vibratory motion of the plate 42 is accomplished by means of a link 45, which is connected, as seen in Fig. 3, with the vibrating lever 34 to move simultaneously with the feed motion of the turret. The normal position of the escapement is with a solid portion of the upper edge of its bridge projected across the slot in the raceway, so as to arrest the descending column of tacks. The tacks are delivered to the tack receiver and carrier one by one.

It will be understood that in the normal upward position of the tack receiver and carrier the latter is in alignment with the tack chute or raceway and forms a continuation thereof, so that the tack, released by the escapement, emerges from the chute into the pocket of the tack receiver and carrier with its point turned down, as before described.

The anvil in which the button is placed may consist of a plate 46, having a cavity 47, in which the button is placed, within which is a pin 48, and this plate 46 is supported upon a

spring-sustained post 49. As shown, the preferred form of anvil is adjustable; but the invention is not limited to any particular form of anvil or button-support.

I have thus described in detail the construction which at this time is deemed the best for carrying out the principle of my invention; but I wish to be understood as not limiting my invention to such details, excepting as the same are hereinafter made specific parts of the claims.

The operation has already been sufficiently indicated in the foregoing description, but may be summarized thus: Tacks having been placed in the turret and the machine properly supplied with power through the medium of the band-wheel 4 and the button having been placed in the button-cavity 47, with its shank end up, the garment to be supplied with buttons is placed over the button-shank, and a tack having been released by the escapement through slot 44 descends through the twisted part of the chute or raceway and enters the notch in the pocket of the tack receiver and carrier with its point down, as indicated in Fig. 4, and then the plunger descends and carries with it the receiver and carrier until the point of the tack has pierced the garment and has entered the shank of the button, at which time the lump on the cam 6 engages the rocker-arm 27 and through shank 23 and arm 20 vibrates the rod 21 and swings out the tack receiver and carrier into the dotted-line position, Fig. 5, and releases the tack and permits the further descent of the plunger for the clenching of the tack in the button and the consequent setting of the button upon the garment. The pin 48 serves also as an anvil or support to prevent the deformation of the button-face. As soon as the button is set the plunger is carried up, and as its active end passes the plane of the descended receiver and carrier said receiver and carrier is swung back again into normal position beneath the plunger and carried up into alignment with the tack chute or raceway, ready to receive the next tack to be set, the escapement at this point being again vibrated to release another tack.

What I claim is—

1. In a button-setting machine, having an overhanging arm, a tack-containing turret, a raceway discharging therefrom, a reciprocating plunger, the combined tack receiver and carrier comprising a rod 16 supported in a bearing in the overhanging arm independently of the plunger, a pocketed arm 17 rigid on said rod adapted to align with the raceway to receive a tack therefrom and present it beneath the plunger, a spring 21 normally elevating said rod and arm, a crank-arm 20 fixed to turn said rod and permitting longitudinal movement of the rod through it, means to rock said crank-arm, and means to depress said plunger and thereby cause the said plunger to carry the said receiver and carrier with it in its descent away from the

raceway and into proximity to the object to which the tack is to be applied, substantially as described.

2. In a button-setting machine of the class described, having an overhanging arm and a reciprocating plunger therein, the combined tack receiver and carrier comprising a rod 16 having a bearing in the overhanging arm independently of the plunger, and capable of 5 longitudinal and rotary movement in said bearing, a pocketed arm 17 rigid on said rod and a spring 21 normally holding the pocketed arm in operative alinement with the plunger and beneath it, combined with a crank-arm 20 keyed 10 to the rod and adapted to turn it and also permitting free longitudinal movement of the rod through it, and means to vibrate said crank-arm, substantially as described.
- 15 3. In a button-setting machine of the class described, having an overhanging arm and a

reciprocating plunger therein, the combined tack receiver and carrier comprising a rod 16 having a bearing in the overhanging arm independently of the plunger, and capable of longitudinal and rotary movement in said bearing, a pocketed arm 17 rigid on said rod and a spring 21 normally holding the pocketed arm in operative alinement with the plunger and beneath it, combined with a crank-arm 20 keyed 25 to the rod and adapted to turn it and also permitting free longitudinal movement of the rod through it, a link 23, rocker-arm 24, a cam-disk and connections between the said disk and rocker-arm, substantially as described. 30

In testimony whereof I have hereunto set my hand this 24th day of December, A. D. 1900.

FREDERICK E. STANLEY.
